UNITED STATES PATENT OFFICE.

HENRY BLUHM AND JOSEPH H. REGAN, OF BOSTON, MASSACHUSETTS.

FURNACE.

No. 882,616.

Specification of Letters Patent. Patented March 24, 1908.

Application filed May 20, 1907. Serial No. 374,593.

To all whom it may concern:

Be it known that we, HENRY BLUHM and JOSEPH H. REGAN, citizens of the United States, and residents of Boston, in the county 5 of Suffolk and State of Massachusetts, have invented an Improvement in Furnaces, of which the following description, in connection with the accompanying drawing, is a specification, like letters on the drawing representing like parts.

Our invention has for its object the improvement of that class of furnace shown in United States Patent No. 468,424, dated February 9, 1892, and relates to a novel construction 15 of the heating surfaces, and the combination therewith of a damper to control the direct and indirect draft.

Figure 1 in vertical section shows a sufficient portion of a furnace with our improvements added to enable our invention to be understood; Fig. 2 is a sectional detail in the line x relating particularly to the damper for controlling the direct and indirect draft.

Referring to the drawing, A represents 25 part of the furnace jacket, the same having a top plate A', the jacket being provided with a series of pipes A², any desired number, that lead hot air to the different apartments that the furnace is adapted to heat. The 30 heating surfaces of the furnace comprise a circular exterior wall B, and a cone-shaped inner wall C, a cone-shaped portion B' sustaining the outer wall B resting on the upper end of the fire-pot B². These devices are 35 and may be all substantially as provided for in the furnace built under the patent referred to.

In accordance with our invention, instead of riveting together the upper ends of the walls B, C, we have closed the space between 40 the upper ends of said walls by a cast metal ring E having a central down-turned flange e and e', e'', and to hold this metal ring gas-tight between the upper ends of said plates, we may place any usual luting between the 45 flanges e', e'' and the upper ends of the plates B, C, and we unite the ring referred to to the walls B, C by adding to wall B a bracket e³ and to wall C a bracket e⁴, and these brackets are connected respectively by tie rods e⁵, e⁶ 50 with the ears e', e'' of the ring E.

The central heating drum D is provided at its top with a cap D' having a flange d to fit the upper end of the drum D, the edges of the cap D' being extended beyond the

drum and provided with holes for the reception of tie rods d' that enter like lugs d² suitably united to the drum. The lower end of the drum is fitted to an upturned flange f of a ring F provided with a series of lugs f', f'', said lugs being shown as provided with slots 60 with which are engaged respectively the lower ends of tie-rods f³, f⁵, the upper ends of said tie-rods engaging respectively lugs f⁴ connected with the drum, and lugs f⁶ connected with the inner wall C, said tie rods sustaining said ring. The outer jacket of the furnace will be opened suitable for the reception of cold air, a portion of which will enter the pipe C^x which leads through the space between the inner and outer wall, said 70 pipe leading into the chamber between the inner wall and the drum so that the cold air has great opportunity to be heated in the space between the inner wall and the drum.

The outer wall B at a distance below its 75 top is provided with a smoke pipe c that is led outwardly through the jacket A of the furnace, and has connected with it in usual or suitable manner the usual smoke pipe leading to the chimney. To provide for controlling 80 the combustion of whatever fuel is deposited on the usual grate, not shown, in the fire-box B², we provide a damper b³ having a handle b⁴ extended outwardly through the jacket A. This damper comprises a central 85 shaft with a circular plate connected therewith, and it coacts with a collar b² shown best in Fig. 2, the collar having two stops 2, 3, one at each side the shaft 4 carrying the damper. The collar b² is located at the lower end of a 90 frame H comprising two baffle-plates h, h', the baffle-plate h being the longer and extending from the collar b² upwardly to the flange e of the ring E, whereas the baffle-plate h' is shorter so that the products of 95 combustion may readily pass over the top of said shorter baffle-plate when the damper is closed, as shown in full lines. The frame H constructed as described, insures, when the damper b³ is closed, that the products of 100 combustion travel about the heating surface in the space between the walls B and C in the direction of the arrows, Fig. 2, and arriving at the shorter baffle-plate h', pass over the top thereof and enter the smoke pipe. 105 When, however, the damper is open, as shown by dotted lines, the products of combustion thrown off from the consuming fuel

may enter immediately the smoke pipe. After the fire is started the damper b^4 is closed. If desired, the smoke pipe outside the jacket A may have a damper and any cold air slide such as commonly used.

We have not herein shown the door through which fuel is fed into the furnace as the same may be as common to the patent referred to, or any other coal-burning furnace.

10 Having described our invention, what we claim as new and desire to secure by Letters Patent is:—

1. In a furnace, a heating surface comprising outer and inner walls, a central dome having a cap, a ring sustaining the lower end of said dome and fitting the lower end of said inner wall, said inner wall, ring and dome each having ears, and tie rods to connect said ring respectively with the ears of the dome and inner wall.

2. In a furnace, an outer and inner wall, each having ears, combined with a ring resting upon the upper ends of said walls, said ring having a flange depending between said

25 walls, tie rods to connect said ring respectively with the ears of said outer and inner walls, a central dome having a cap, a ring sustaining the lower end of said dome and fitting the lower end of said inner wall and tie

rods connecting said last mentioned ring respectively with said dome and inner wall.

3. In a furnace, a heating surface comprising an outer and inner wall, the outer wall having a smoke pipe, combined with a frame interposed between said walls, said frame having baffle-plates differing in height, and a damper in the bottom of said frame, said damper when closed insuring the passage of the products of combustion about said heating surface between said inner and outer walls and over the shorter baffle-plate into the smoke-pipe.

4. In a furnace, a heating surface comprising outer and inner walls, a smoke pipe connected with said outer wall, a frame presenting baffle-plates of different height, and a damper at the lower end of said frame said damper when opened permitting the products of combustion to pass immediately from the grate into the smoke pipe.

In testimony whereof, we have signed our names to this specification, in the presence of two subscribing witnesses.

HENRY BLUHM.
JOSEPH H. REGAN.
